UNITED STATES PATENT OFFICE.

WILLIAM E. GOOD, OF PHILADELPHIA, PENNSYLVANIA, ASSIGNOR TO THE SOUTHWARK FOUNDRY AND MACHINE COMPANY, OF SAME PLACE.

STEAM-ENGINE.

SPECIFICATION forming part of Letters Patent No. 448,184, dated March 10, 1891.

Application filed December 29, 1888. Serial No. 294,954. (No model.)

To all whom it may concern:

Be it known that I, WILLIAM E. GOOD, of the city and county of Philadelphia, State of Pennsylvania, have invented a new and useful Improvement in Steam-Engines, of which the following is a true and exact description, reference being had to the accompanying drawings, forming a part of this specification.

My invention relates to the construction of steam-engines, and particularly to single-cylinder compound engines.

In the accompanying drawings I have illustrated an engine provided with my improvements, the nature of which will be best understood after explaining the drawings, and which are hereinafter clearly pointed out in the claims.

In the drawings, Figure 1 is a side sectional elevation on the line $x-x$ of Fig. 2. Fig. 2 is a front sectional elevation on the line $y-y$ of Fig. 1. Fig. 3 is a front view of the door R' , reduced in size to save space. Figs. 4 and 5 are sectional views of the steam-ports and valve, showing the valve in different positions. Fig. 6 is a side view of the governor, and Fig. 7 a cross-section on the line $z-z$ of Fig. 6.

A is the cylinder, having, as shown, an extension A' of large though smaller diameter, which serves as a stuffing-box and guide for the trunk-extension of the piston.

B is the piston fitting in the cylinder A and attached to and forming a part of it, as what I will call a "trunk-piston" B' , fitting in the extension A' of the cylinder A . The piston is a differential one, and, as will be seen, steam admitted on the under side of piston B acts on its annular face B^3 , while when admitted on the upper side it acts on the whole surface of the piston. There is an opening A^3 formed through opposite sides of the end of the extension A' of the cylinder, a similar opening B^3 being formed in the end of the trunk-piston B^3 , these openings being arranged to register with each other when the piston is in its lower position, and being for the purpose of permitting easy access to the pin connecting the piston and connecting-rod.

D is the connecting-rod; C , the main shaft; C' , the crank, and E the pin by which the

piston and connecting-rod are attached to each other.

As shown in the drawings, the connecting-rod D is made up of a continuous strap D' , holding journal-boxes F F' in its ends, and a stout rod D^2 , bearing against the ends of the journal-boxes. This rod should be threaded and provided with a nut or nuts, so that by turning it the boxes can be forced apart. As shown, the upper end d^1 of the rod is rounded and fitted in a socket f in the box F and the lower end d^2 threaded and fitted in a nut f' , formed in or attached to box F' , d^3 being a jam-nut to lock the rod in position instead of a screw, its familiar mechanical equivalent. The wedge may be used to force the rod D against the boxes.

d^5 is a cup on the top of strap D' , from which an oil-hole leads to the pin E , as shown, and the piston B is made with a downward curve, terminating in a point b , arranged centrally and above cup d^5 , so that any oil thrown against the piston will flow from said point b into the cup, thus keeping the pin E lubricated.

G' is the port leading to the lower end of cylinder A , and G the port leading to its upper end, these ports being, as shown, formed in a valve-box H , forming part of the same casting as the cylinder.

I is the valve, having formed in it ports or passages i i' i^2 , which, as shown in the drawings, are properly arranged and proportioned with respect to the mouths g^3 and g of the ports G' G . By making the passages i i' i^2 open at the top, as shown, and recessing the valve-box bonnet, as at g^3 g' g^4 , forming these recesses of corresponding area to the mouths of ports G' , G , and J and opposite to them, the valve is balanced and at the same time the extent to which the ports G' are opened as the edges of the valve pass over them practically doubled.

J is the steam-passage leading from a steam-pipe (indicated by dotted lines) to the valve, as shown.

K is the blow-off or exhaust pipe.

U' , Figs. 4 and 5, is a valve in port G , through the wall of which a passage U is made to the exhaust-pipe, as shown.

u is the valve-stem, and u' a light spring. This device is intended to be used when my engine is not used as a condensing-engine, so that when the pressure in port G falls below the atmospheric pressure air preferably drawn from the exhaust, so as to be hot, may be admitted to the cylinder. It is held to its seat over passage U by a light spring.

L is the valve-rod; L', the eccentric-strap to which rod L is attached.

M is the eccentric, (and here I will call attention to the fact that the main shaft C is provided with a square block C², formed around it in forging or casting and centrally perforated, as shown at C³. I prefer also to to form a square block at C⁴, also perforated, as at C⁵, for the purpose hereinafter specified.) The eccentric is provided with a square opening M' of a form to fit neatly on the block C² on two sides, but longer than the block in the other direction, as shown in Fig. 7, so that it can slide on it. The eccentric is held in place on the block in any convenient way, as by a collar c, Fig. 6.

N is a link pivoted to the eccentric by a pin m⁴, resting in a bearing m³ in the eccentric, said link extending up through the perforation C³ of block C² and being pivoted at its top, as shown, to a lever O, which lever is pivoted at o to lugs C⁶, formed on or attached to the shaft C, and is provided with a weight O' at its other end. The weighted lever O is held against the shaft, as shown in Fig. 6, by a spring of regulated power. As shown, the spring P passes through a perforation C⁵ in the block C⁴ on shaft C, said perforation being preferably slightly inclined, as shown, and is secured to an eyebolt P', which is secured in a cup or bell Q by a nut P².

An important feature of the construction above described is that the pins p and the one marked n are all so inclosed that when the governor is put together they cannot get out of place, as in each case they abut against solid walls of metal.

R is the casing of my engine. As shown, this casing is attached to the cylinder and incloses all the moving parts outside of the cylinder. The bottom of this casing is to be filled with oil and water, as is usual in such engines. To permit easy access to the mechanism within this casing, I provide a door R' with a gasket r, by which it makes a tight joint when closed, said door being hinged at one side, as shown at r², and having a fastening or fastenings, as r³, adapted to press it close to the casing and effect a tight closure thereof.

S is a pipe connecting with the interior of casing R and terminating in a nozzle situated in a pipe K', connected with and forming part of the exhaust-passage K, as shown.

The operation of my improved engine is as follows: First, as to the cylinder and piston, in Fig. 1 the valve I is shown with its port i just opening into the port G', so that the high-pressure steam from the port J can enter G',

and in Fig. 4 the valve has moved up to open this passage to the full extent. It will be noticed that while the steam is entering G' the valve-port i² connects the port G with the exhaust-pipe, as shown. The high-pressure steam acting on the annular face B² of the piston forces it up, and the air or steam on the other side escapes freely through K. The valve, having accomplished its full upward stroke, moves backward, closing the passage between ports J and G' at such a point in the upward motion of the piston as may be determined by the governor and the setting of the valve and permitting the steam to expand in the cylinder until the piston reaches its uppermost position, at which point the valve is in such a position as to close the exit-passage and connect the ports G' and G through port i' i², as is shown in Fig. 5, which represents the valve position after the piston has begun to move downward. The steam then passes from the lower part of the cylinder through ports G', i', i², and G to the top of the cylinder, acting on the face B of the piston as it expands and forcing it down, as the face B greatly exceeds the annular face B² in area. At the end of this downward motion the valve moves up to open passage K and the described operation again begins. The motion of the trunk-piston B', open, as it is, to the chamber formed by casing R, will naturally alter the atmospheric pressure in it and tend to blow oil through any opening, as along the shaft C or the door R'. To overcome this, I have devised the plan of connecting the chamber with the escape-pipe by means of pipe S, the nozzle S' of which is surrounded by and in line with the pipe K'. The escaping steam of course creates a suction in pipe S, as the arrangement of nozzle S' and pipe K' is in effect an ejector, and the pressure in the casing R is thus maintained at somewhat less than that of the atmosphere.

It is of course to be understood that the engine represented is one of very high speed, and the escape of steam is so constant that there is a practically constant suction in pipe S. Even at lower speeds the device will be useful as affording a ready escape for air in casing R.

The action of the governor is as follows: As shown in Figs. 6 and 7 the eccentric is in its position of greatest throw, its eccentricity being represented by the distance between m and m', Fig. 7, which distance is the resultant of the distance m' m² by which the center of the eccentric is away from the center of the shaft in the direction in which it moves on said shaft and the distance m m² by which the center of the eccentric is away from the center of the shaft in a direction at right angles to m' m². As the speed of shaft C increases, the weight O' of course tends to fly away from it, this action being counteracted by spring P, and as the centrifugal force of the weight gradually exceeds the power of the spring it moves out, forcing the

end of lever O, connected with link N, down and by means of said link causing the eccentric to move on its square bearing C² in the direction which in Fig. 7 is downward, toward M², thus shortening the throw of the eccentric until it reaches its minimum, which is equal to the distance between m and m², Fig. 7, the point m³ then coinciding with m', at which point the valve would open the connection between J and G' to the extent of the lead of the valve only, and if allowed to move farther, so that m³ would be on the other side of m', the motion of the valve would be changed to reverse the engine.

Having now described my invention, what I claim as new, and desire to secure by Letters Patent, is—

1. In combination with a vertical single-cylinder compound engine having a cylinder A with extension A' and a piston B, working in the cylinder, with a hollow trunk-extension B', working in the extension A', said piston B having a downwardly-curved and centrally-pointed form b, a pin E, secured in the trunk-piston B', and a connecting-rod D, coupled to the piston by pin E and having an oil cup and hole d⁵, situated below the point b.

2. In a single-cylinder compound engine, a cylinder A, having a prolonged extension A', having openings A³ in its sides, in combination with a piston B, working in the cylinder, a trunk-extension B' of said piston working in the extension A' of the cylinder end, having openings B³ through its sides so arranged as to register with the openings A³ at the bottom of the stroke, a pin E, secured in the trunk-piston B', and a connecting-rod having bearings on said pin, all substantially as and for the purpose specified.

3. In a single-cylinder compound engine, a cylinder A, having an extension A', a piston B, working in cylinder A and having a trunk-extension working in extension A' of the cylinder, ports G' G, exhaust K, steam-port J, and valve I, having ports i i' i², adapted to register with ports J G' G and exhaust K, as specified, all substantially as shown and described.

4. In a single-cylinder compound engine, a cylinder A, having extension A', a piston B, working in cylinder A and having a trunk-

extension working in extension A' of the cylinder, ports G' G, exhaust K, steam-port J, valve I, having ports i i' i², adapted to register with ports J G' G and exhaust K, as specified, a valve-rod and eccentric-strap, a rotating shaft C, made with straight sides at C² and with a perforation C³, an eccentric M, having a slot M', by which it is secured to the shaft and free to slide thereon, a joint-pin m⁴, secured in the eccentric, a link N, extending from pin m⁴ through perforation C³, a pivoted weighted lever O, attached to said link, and a counterbalancing-spring arranged to resist the momentum of weighted lever O, all substantially as and for the purpose specified.

5. In a single-cylinder compound engine, a cylinder A, having extension A', a piston B, working in cylinder A and having a trunk-extension working in extension A' of the cylinder, ports G' G, exhaust K, steam-port J, valve I, having ports i i' i², adapted to register with ports J G' G and exhaust K, as specified, a valve-rod and eccentric-ring, a rotating shaft C, made with straight sides at C² and square block at C⁴, said squares C² C⁴ having perforations C³ C⁵ passing through them, an eccentric M, having a slot M', by which it is secured to the shaft and free to slide thereon, a joint-pin m⁴, secured in the eccentric, a link N, extending from pin m⁴ through perforation C³, a pivoted weighted lever O, attached to said link, and a counterbalancing spring arranged in perforation C⁵, an eyebolt to hold said spring, and a cup to secure said bolt on the side of the shaft opposite to the lever O, all substantially as and for the purpose specified.

6. In combination with a vertical steam-engine having a trunk-piston extending out of its cylinder and a connecting-rod working on a pin secured in the trunk-piston, the device of forming the head of the piston with a downwardly-extending point, in combination with an oil hole and cup in the top of the connecting-rod.
